UNITED STATES PATENT OFFICE.

JOHAN ABRAHAM OHLSSON, OF STOCKHOLM, SWEDEN.

SAFETY-RAZOR.

1,083,026.

Specification of Letters Patent. Patented Dec. 30, 1913.

Application filed October 23, 1911. Serial No. 656,258.

To all whom it may concern:

Be it known that I, JOHAN ABRAHAM OHLSSON, a subject of the King of Sweden, and resident of Tegnérsgatan 45, Stockholm, 5 in the Kingdom of Sweden, have invented certain new and useful Improvements in Safety-Razors, of which the following is a specification, reference being had therein to the accompanying drawing.

10 This invention relates to improvements in safety razors of that class, in which the blade has an oblique edge or converging edges and is adjustable with relation to the correspondingly shaped guard, so that the 15 action of the razor can be adapted to different kinds of bristles. According to this invention the holder for the said blade, when having converging edges, is provided with a longitudinal recess in which the 20 blade and the guard, each provided with a longitudinal slot, are inserted, the said blade and guard embracing a guide for the same, provided in the holder between the walls of the recess. If the blade has 25 only one cutting edge, the guide is located at one edge of the holder and the slots in the blade and guard for engaging the guide are formed by hooks on the back edges of the blade and guard. In consequence of the 30 said arrangements the construction of the safety razor, *i. e.*, the blade, the guard and the holder, is very simple and after the shaving operation has been finished, the razor can easily be cleaned, the cleaning 35 operation being confined to the blade and the holder, while the guard, if made of pasteboard or any other cheap material, may be thrown away. According to a modified form of the invention the holder is provided with two recesses, one for the blade 40 and one for the guard.

A safety razor provided with two converging edges and arranged in accordance with this invention is shown in the accompanying drawing, in a side view in Figure 1 and in a plan view in Fig. 2. Fig. 3 is a side view and Fig. 4 is an end view of the holder. Figs. 5 and 6 are a plan view of the guard and the blade respectively. 45 Fig. 7 shows a modification. Fig. 8 is a plan view of a safety razor arranged in accordance with this invention and with the blade provided with only one oblique edge. Fig. 9 is a section on the line 9 to 9 50 of Fig. 8. Figs. 10 and 11 show the blade and the guard respectively.

1, Figs. 1 to 4 inclusive, is the holder fixed to or, as shown, made integral with the handle 2. The flat holder 1 has a longitudinal recess 3, extending from its edges to the vicinity of its center line, a part 4 with parallel sides being left, which connects the two halves of the holder and serves as a guide.

5 is the blade, see also Fig. 6. The said blade has two converging edges 6, 6 and a central, longitudinal slot 7, extending from the long end of the blade to the vicinity of the opposite short end of the same. The said slot 7 is so adapted that the blade 5 60 can be pushed into the recess 3, embracing with its slot 7 the part 4 of the holder, as shown in Fig. 2.

The guard 8, see also Fig. 5, consists of a flat piece preferably of thin, stiff pasteboard or any other suitable cheap material but may be made of sheet metal, celluloid, ebonite or the like. The edges of the said guard 8 converge in the same or substantially the same degree as the edges 6, 6 of 65 the blade 5 and are provided with teeth 9, which, in the well known manner, have a protecting action during the shaving operation. The said guard has a longitudinal, central slot 10, so that the guard can be 70 pushed into the recess 3 of the holder 1, embracing the part 4 of the same and the portions located on opposite sides of the slot 10, as shown in Fig. 2.

The blade 5 and the guard 8 are pushed into 75 the recess 3, until the bottom wall of the slots 7 and 10 respectively bears against the outer end of the part 4. The edges 6, 6 of the blade 5 are then parallel or substantially parallel to the toothed edges of the guard 8 80 and located at some distance inside the same. The width of the recess 3, is so determined that the blade 5 and the guard 8 are held in the holder by their friction with the side walls of the grooves. When the 85 safety razor is used, the distance between the edges 6, 6 of the blade and the free ends of the protecting teeth 9 can be changed by moving the blade 5 or the guard 8 for a short distance from the position shown in 90 Fig. 2, and the razor thus be adapted to the sensibility of the skin and to coarser or finer bristles. During the shaving operation all or substantially all the lather and the 95 bristles shaved off will gather on the guard 8, which is then removed from the holder 100 and cleaned. The slight quantity of lather, 105

which sticks to the blade and the holder can easily be removed even without the blade being separated from the holder. Consequently, the cleaning of the razor, which is confined chiefly to the guard, can easily be effected, and if the guard is made of pasteboard or any similar cheap material, it may be thrown away, so that only the blade and holder need be cleaned. After the guard has been removed, the blade can be sharpened or stropped while being located in the holder. The edges 11, 11 of the holder converge in the same or substantially the same degree as the edges of the blade, so that the holder serves as a guide during the sharpening or stropping operation by being held in contact with the strop. Owing to the fact that the blade and the guard are locked to the holder only by the friction between the said parts, no screws or similar means are necessary for the said purpose, which can be lost and thus render the razor unfit for use, until fresh screws, etc., have been procured.

In the modification shown in Fig. 7 the holder 1 is provided with two recesses 12, 13 for the guard and the blade respectively. In other respects the safety razor is arranged as described above.

In the form of the invention, shown in Figs. 8 to 11 inclusive and adapted to a blade, having only one oblique cutting edge, the holder 14 is formed preferably by a piece of sheet metal being so folded, that a longitudinal groove is effected, into which the blade 15 and the guard 16 can be pushed and in which they are held by their friction with the inner sides of the shanks of the holder, U-shaped in cross section, as shown in Fig. 9. The holder 14 is preferably formed by a sheet of metal having two converging edges, so that, when the said piece is folded up, the said edges are substantially parallel with the cutting edge of the blade 15. In

order to cause the blade and guard to occupy a predetermined position with relation to the holder and to each other and with the edge of the blade located at some distance from the free ends of the teeth of the guard, inside the said ends and parallelly to the same, the parts 17 and 18 of the blade 15 and the guard 16 respectively, located on the back edges of the blade and the guard, form hooks which engage the back 19 of the holder 14, the said back forming a guide and performing the functions of the guide 4 hereinbefore referred to. When the blade 15 is moved longitudinally of the holder in order to adapt the distance of its edge from the free ends of the teeth of the guard to different kinds of bristles, the said hook-shaped parts 17, 18 will keep the edge of the blade in the said position parallel with the free ends of the teeth of the guard. After the guard has been removed, also in this construction the blade can be sharpened or stropped while located in the holder.

The invention may, evidently be applied also to razors the construction of which differs from those described above.

Having now described my invention, what I claim as new and desire to secure by Letters Patent is:

In a safety razor, the combination of the blade provided with a longitudinal slot, a free guard provided with a longitudinal slot, and a holder provided with a guiding part and recessed to permit the said blade and guard to be slid therein and embrace the guiding part.

In witness whereof, I have hereunto signed my name in the presence of two subscribing witnesses.

JOHAN ABRAHAM OHLSSON.
